UNITED STATES PATENT OFFICE.

ABRAHAM HENRY WORMALD, OF SHEFFIELD, ENGLAND, ASSIGNOR TO
THE WORMALD PATENT LOCKS COMPANY, LIMITED, OF SHEFFIELD,
ENGLAND.

KEY.

SPECIFICATION forming part of Letters Patent No. 711,889, dated October 21, 1902.

Application filed June 20, 1902. Serial No. 112,490. (No model.)

To all whom it may concern:

Be it known that I, ABRAHAM HENRY WORMALD, out of business, a subject of the King of Great Britain and Ireland, residing at Cemetery road, Sheffield, in the county of York, England, have invented certain new and useful Improvements in Keys, (for which I have made an application in Great Britain, No. 18,630, dated September 18, 1901,) of which

10 the following is a specification.

This invention relates to locks and keys, and has for its object to prevent picking of such locks.

The invention consists in the features and 15 combinations and arrangement of parts hereinafter described, and pointed out particularly in the claims.

In the accompanying drawings I have illustrated the improved key and a lock capable 20 of being operated by such a key.

Figure 1 is a side elevation of the improved key. Fig. 2 is a section thereof. Fig. 3 is an end view of Fig. 1. Fig. 4 is an end view of Fig. 2. Fig. 5 is a face view of the lock, and 25 Fig. 6 is a face view showing the locking parts with the front plate and shackle removed.

My improved key (shown in Figs. 1 to 4) consists of a housing *a*, within which can be slid a sleeve *b* against the action of the coiled 30 spring *b'*. The sleeve *b* is formed with a fixed wing *c*, another wing *d* being pivoted to a spindle *e*, fixed to the housing *a*. Normally the key is provided with one projecting wing *c* only, the hinged wing being recessed with 35 in the sleeve *b*, as shown in Figs. 1 and 3. When the key is pushed home and end pressure is applied to the housing *a*, the sleeve *b* is slid within the housing and the wing *d* is protruded out of the sleeve *b*, as explained 40 in my former patent and as shown in Figs. 2 and 4 of the present application—that is, the wing passes out through a slot *d'* in the shell of the sleeve *b*, the said wing having a curved edge at *d'*.

45 The lock used with such a key is indicated in face view in Fig. 6, and consists of a bolt *g*, slideable on a stud *g'* against the pressure of a spring *h*. A locking-lever *i*, maintained in position by a spring *k*, engages with the 50 bolt *g*, preventing the same from being operated until the part *i'* has been withdrawn from the notch *j*, formed on the bolt *g*. The key

is inserted in the lock, and end pressure is applied to protrude the wing *d* out of the sleeve *b*. The key is then rotated, the fixed 55 wing *c* coming first into contact with the locking-lever *i*, withdrawing the part *i'* from the notch *j*, the wing *d* then sliding back the bolt *g*. When the key is withdrawn, the springs *h* *k* return the sliding bolt *g* and locking-lever 60 *i* into their normal positions.

As the key normally is provided with only one projecting wing *c*, only one slot *f* is necessary in the front plate of the lock. It is evident, therefore, that as two wings or operating-wards must be used to actuate the lock 65 the lock cannot be picked.

The essential feature of my invention consists in the combination, with a key of any ordinary or suitable construction, of a recessed 70 wing, which being housed within a shank of the key requires no slot for its passage in the front plate of the lock, but which can be brought into action within the lock to provide an additional wing or projection to operate the 75 lock. Whatever, therefore, the number of wards or projecting wings are required to actuate the lock, the key-plate can be formed with one slot less than such a number, thus rendering it impossible to insert a pick-lock 80 capable of operating the lock.

I declare that what I claim is—

1. In combination in a key a housing *a*, a sleeve *b*, a fixed projecting wing *c* secured to the sleeve, a spindle *e*, a wing *d* pivoted to 85 the spindle, and means for protruding the pivoted wing *d* out of the sleeve *b* substantially as described.

2. In combination in a key, a housing *a*, a sleeve *b* slideable therein and carrying a rigid 90 bit or wing said sleeve having a closed end and lateral opening, a spindle *e* within the sleeve and housing, a coiled spring encircling the rod within the housing and bearing against the end of the sleeve and a pivoted bit having a rounded edge adapted to bear against said closed end and be projected through said lateral opening.

In witness whereof I have hereunto set my hand in presence of two witnesses.

ABRAHAM HENRY WORMALD.
